2.615.380

CONTACT PRINTING MACHINE WITH PHOTOTYPE

**Joseph F. Murphy, West Roxbury, Mass., assignor
to Lumitype Corporation, Roxbury, Mass., a
corporation of Massachusetts**

Application December 1, 1948, Serial No. 62,895

1 Claim. (Cl. 95—73) **1** A printing frame for use in a printing machine, comprising a rectangular frame having a top and bottom side and a pair of end members, the top and bottom sides being provided with oppositely arranged slots in which may be placed in selected positions the ends of cross bars **19**. These bars have inverted T-shaped cross-section and so provide type supporting ledges on both sides which cooperate with the ledges of the side and end members of the frame.

The present invention comprises a new and improved machine for contact printing adapted for the employment of individual type blocks having transparent letters formed in reverse therein so that any desired display type may be set up rapidly and reproduced conveniently by contact printing.

The principal object of the invention is to provide the small offset printer with a photographic lettering machine having a wide variety of fonts of various point type display faces. The equipment of my invention provides the printer with a wide range of type faces, for example, from 36 point to 144 point, and the machine includes means whereby the type may be rapidly assembled in perfect alignment. Preferably the individual type blocks comprise a clear plastic body coated with opaque varnish or the like, in which are formed the negative characters. If desired both upper and lower faces of the type blocks are treated with protective varnish which prevents scratches in wear and repeated use.

The individual type blocks are accurately machined and fit smoothly together so as to prevent light from passing through the assembled blocks except within the contour of the transparent negatives.

These and other features of the invention will be best understood and appreciated from the following description of a preferred embodiment thereof, selected for purposes of illustration and shown in the accompanying drawings in which:

Fig. 1 is a plan view of the type holding portion of the machine showing typical type blocks in place.

Fig. 2 is a sectional view on the line 2—2 of Fig. 1.

Fig. 3 is a view in perspective of the complete machine and

Fig. 4 is a view in perspective of a single type body.

The machine as herein illustrated comprises a casing 10 having a stationary cover section 11 to which is hinged a two-part cover 12-13 connected to an operating lever 14. The casing 10 contains an electric lamp which is controlled by a switch not shown.

The top of the casing 10 is provided with a horizontal type holder which is best shown in Fig. 1. This comprises side members 15 and 16 and end members 17 and 18 forming a horizontally disposed frame. All of the frame members are shouldered to provide an inwardly projecting ledge extending about the four sides of the frame. The end members 17 and 18 are pro-

(Cl. 95—73) **2**
vided with oppositely arranged slots in which may be placed in selected positions the ends of cross bars 19. These bars have inverted T-shaped cross-section and so provide type supporting ledges on both sides which cooperate with the ledges of the side and end members of the frame. The individual type blocks employed in connection with the frame are of the character shown in Fig. 4, that is to say, the rectangular body is of transparent resinous material such as "Lucite." The sides and upper surfaces are coated with an opaque varnish in which is depicted in reverse the transparent outline of a letter. For example, in Fig. 4 the type body 20 has an opaque coating 21 defining the contour of a transparent "e" 22. Each type block is also provided at its upper end with a spot 23 which indicates visually to the printer how the type block should be placed in the supporting frame. The spot is located symmetrically above the outline of the letter and in the marginal portion of the block which overlaps the supporting ledge of the frame or cross bar.

The notches in the end members of the frame are so arranged that the bars 19 may be located with the proper spacing to support type blocks of the desired different sizes. As shown in Fig. 1, the side frame member 16 and one of the bars 19 support type blocks 24 displaying capital letters in 80 point size. Two of the intermediate bars 19 support type blocks 25 displaying transparent figures in 36 point size, and another pair of bars 19 support type blocks 26 displaying letters in 48 point size. When the type blocks are arranged with the longitudinal edges in contact, their opaque coating forms a continuous screen and no light can pass through the assembly except in the transparent areas depicting the letters.

- 0 When the type has been set in the holder, the printer places a sheet of photographic paper immediately on the type form. The cover is then pulled down, holding the paper and type together in close and continuous contact and the light within the casing is turned on for a predetermined interval, generally determined by an automatic timer. The exposed paper is then removed and developed whereupon the type is reproduced as a positive impression on the paper. The printer may then use this paper positive as a paste-up for rephotographing, or he can use film on the printer for plating.

Preferably and as herein shown, a thin layer 24 of transparent lacquer, which may be of any suitable plastic material, is laid over the face of

the type block. This forms a protective shell that keeps the face of the type clean and stain-proof. It is impervious to grease and perspiration, and any dirt falling thereon may readily be removed. The lacquer coating is perfectly united to the type face without wrinkles or blemishes.

Having thus disclosed my invention and described in detail an illustrative embodiment thereof, I claim as new and desire to secure by Letters Patent:

A contact printing device for holding type blocks having thereon transparent letters, said device comprising a rectangular lamp-enclosing casing presenting at its top a type holder which includes in its structure a rectangular frame having side members and transverse end members all shouldered and providing a continuous marginal ledge inside the casing, the end members having upwardly opening slots at oppositely located points, and a series of transverse bars removably fitting into the slots of the end members and retained in spaced position thereby and

having ledges on both sides disposed at the same level as the marginal ledges, a hinged cover overlying the area of the type holder, and an operating handle for the cover.
